UNITED STATES PATENT OFFICE.

EDMOND A. FORDYCE, OF BOSTON, MASSACHUSETTS, ASSIGNOR TO LAMSON CONSOLIDATED STORE SERVICE COMPANY, OF NEWARK, NEW JERSEY, A CORPORATION OF NEW JERSEY.

PNEUMATIC-DESPATCH-TUBE APPARATUS.

968,141.

Specification of Letters Patent. Patented Aug. 23, 1910.

Application filed February 13, 1905. Serial No. 245,332.

To all whom it may concern:

Be it known that I, EDMOND A. FORDYCE, of Boston, in the county of Suffolk and State of Massachusetts, have invented certain new and useful Improvements in Pneumatic-Despatch-Tube Apparatus, of which the following is a specification.

My invention relates to improvements in pneumatic despatch apparatus and its object is to devise an apparatus on the vacuum principle which is effective and economical and through which air passes only when the apparatus is in use transmitting carriers.

My invention consists of certain novel features hereinafter described and particularly pointed out in the claims.

In the accompanying drawings which illustrate a construction embodying my invention, Figure 1 is a side elevation partly in section of the apparatus. Fig. 2 is a side elevation showing the position of the parts when a carrier is introduced up into the tube at the central station for transmission to a substation. Fig. 3 is a side elevation of the apparatus showing the position of the parts upon the introduction of the carrier at a substation for transmission to a central station. Figs. 4 and 5, are enlarged detail sectional views to be described.

Like letters of reference refer to like parts throughout the several views.

The transit tube A for transmission of the carriers from the central station to a substation has a bell-mouth opening B to receive the carriers for transmission. Above said mouth B there is pivoted at C' the valve C, which in the normal condition of the parts closes the tube L leading to the bottom of the cylinder J and hereinafter referred to. The valve C has an inwardly extending finger into the tube A which does not close said tube A but acts simply as a means for causing resistance to the air passing through the tube A, so that there will be a vacuum on the diaphragm L⁴ to hold the same in position as shown in Fig. 4 when a current of air is passing through the tube A, and said finger does not stop the passage of air through the tube A. This finger also forms a trip extending into the path of the carriers for opening valve C when a carrier is inserted. Located above the valve C there is another valve D pivoted at D' and connected to the link E which is connected to the piston rod F by a pin and slot connec-

tion G. The pipe K is connected to the upper end of the cylinder J at one end and at the other end is connected to the exhaust tube K' which leads to a suitable reservoir. Connected to the tube K' is a terminal K² 60 which is also connected at one end to the return tube K³ and is provided with a valve K⁴ which is adapted to open under the impact of the discharging carrier.

The forwarding tube A at the substation 65 enters the terminal A', of usual construction and the carriers are discharged through the valve A² by impact to a suitable receptacle. The suction entering the terminal A' passes into the tube A³ and then into the 70 tube K³ and thence to the exhaust tube K'. In the tube K³ is a suitable inlet for carriers and normally closed by the valve A⁴ which is held in its closed position by the vacuum in the system when the carriers are being 75 transmitted. Located in the transit tube A is a hollow casting L³ and secured in said casting by suitable screws L⁵ is a diaphragm L⁴ to which is connected the rod L⁶ secured at L⁷ to the slide valve L⁸ which controls 80 the port L⁹ of the closed chamber L² connected by pipe L' to cylinder J below piston H. With the parts in the position shown in Fig. 1, it being desired to transmit a carrier from the central station to a substation, 85—the carrier is inserted as shown in Fig. 2 and opens the valve C which allows atmospheric pressure to pass through the pipe L up into the bottom of the cylinder J under the piston H, and there being a 90 vacuum on the upper side of the piston H (due to the pipe K being connected to the exhaust tube K') the atmospheric pressure underneath said piston raises it to the position shown in Fig. 2 opening the valve D 95 which allows a suction through the entire system, drawing the carrier up into the tube and transmitting the carrier and discharging it at the substation. After a carrier has been inserted for transmission and has 100 passed the valve C, said valve returns to its normal position shown in Fig. 1 closing the pipe L from the atmosphere. The suction through the pipe K and through the connection M equalizes the vacuum on both 105 sides of the piston H, which of its own weight drops to the lower position shown in Fig. 1 and closes the valve D.

To return a carrier from a substation to the central station, the attendant raises the 110

valve A⁴ and inserts the carrier into the tube A³. The opening of this valve A⁴ destroys the vacuum in the tube A and allows the diaphragm L⁴ to move to the position 5 shown in Fig. 5, thus opening the port L⁹ to the atmosphere. This destroys the vacuum underneath the piston H and the atmospheric pressure raises the piston H to its upper position shown in Figs. 2 and 3. 10 This allows the air to pass through the tubes A and K³ to the exhauster as the valve D opens when the piston H rises as described. Upon the closing of the valve A⁴, the diaphragm is returned by the suction through 15 the pipes K³ and A to its normal position shown in Fig. 4 and closes the port L⁹, thereby cutting off the atmospheric pressure underneath the piston H, and the vacuum on both sides of said piston due to the pipe 20 K and pipe M being equal, the piston drops of its own weight to its lower position. The valve L⁸ only falls of its own weight when the lid A⁴ is opened which destroys the vacuum between the point A⁴ and the dia- 25 phragm L⁴, the valve L⁸ falling of its own weight and opening the port L⁹, thus de- 30stroying the vacuum in the lower end of the cylinder J, and the piston H rises to the top of the cylinder J, as shown in Fig. 2, and the valve D is opened allowing the flow of 35 air through the tubes A and K³. To send a carrier from the bell mouth end B, the carrier is inserted as shown in Fig. 2, and the valve C is opened, thus destroying the 40 vacuum underneath the piston in the cylinder J, and the piston H rises to the top of the cylinder J; this last operation does not affect the diaphragm L⁴ as the flow of air through the pipe A through the terminal 45 A' and through the pipe K³ thence to the blower or suction drum does not affect said diaphragm. The closing of the air-inlet valve D is timed by the dropping of the piston H, the length of time the valve D is open depending upon the time taken by the 50 piston in dropping, which may be varied by varying the size of the outlet through pipe M. The valve M' located in the pipe M can be adjusted for different lengths of line, 55 that is, in long lines this valve would close the pipe M nearly up, while in short lines the valve would be nearly wide open; this valve M' controls the passage of air through the pipe M, and as more air passes through the pipe K than through the pipe M, the piston will drop slowly and rise readily.

Having thus described the nature of my invention and set forth a construction embodying the same, what I claim as new and 60 desire to secure by Letters Patent of the United States is:

1. In a pneumatic-despatch-tube system, the combination of a normally closed transit-tube through which carriers are transmitted, a sending-station arranged to permit a car-

rier to be inserted into the tube, means for exhausting air from the tube, and a valve adapted to admit air into the tube for driving carriers, said valve being adapted to open through a fluctuation of the pressure 70 within said tube, means normally urging the closing of said valve, and means for timing the closing of said valve.

2. In a pneumatic-despatch-tube system, the combination of a normally closed transit-tube through which carriers are transmitted, an air-inlet valve at one end of the tube and being normally closed, means for exhausting air from the tube near its other end, a plurality of receiving-stations through which 80 carriers may be inserted into the tube, and mechanism for opening said air-valve to admit air for driving a carrier along the tube when the carrier is inserted at either of said receiving-stations.

3. In a pneumatic-despatch-tube system, the combination of a normally closed transit-tube through which carriers are transmitted, an air-inlet valve at one end of the tube and normally closed, means for exhausting air from the tube near its other end, a plurality of receiving-stations through which carriers may be inserted into the tube, and pneumatic means for opening said air-valve to admit air for driving a carrier 95 along the tube when a carrier is inserted at either of said receiving-stations.

4. In a pneumatic-despatch-tube system, the combination of a pair of normally closed transit-tubes connecting two stations and 100 having their receiving and delivery terminals at respectively opposite stations, an air-passage connecting said tubes at one of said stations, suction apparatus communicating with the delivery-terminal at the other station, an air-inlet valve controlling the inflow 105 of air at the receiving-terminal at said other station, said air-valve being normally closed, and mechanism adapted to open said air-valve when a carrier is inserted into either of 110 said transit-tubes.

5. In a pneumatic-despatch-tube system, the combination of a pair of normally closed transit-tubes connecting two stations and 115 having their receiving and delivery terminals at respectively opposite stations, an air-passage connecting said tubes at one of said stations, suction apparatus communicating with the delivery-terminal at the other station, an air-inlet valve controlling the inflow 120 of air at the receiving-terminal at said other station, said air-valve being normally closed, and mechanism adapted to open said air-valve through a change of the pressure in the transit-tubes.

6. The combination of a transit-tube through which carriers are transmitted, a gate extending across the tube and normally closed to prevent the passage of air through 125 the tube, pneumatic means for opening said

gate, a trip extending into the path of the carriers in front of said gate, and said trip being adapted when engaged by a carrier to cause the operation of said pneumatic means for opening the gate to permit the free passage of the carrier.

7. In a pneumatic-despatch-tube-system, the combination of a normally closed transit-tube through which carriers are transmitted,

10 an air-inlet valve at one end of the tube and being normally closed, means for exhausting air from the tube near its other end, a plurality of receiving stations through which carriers may be inserted into the tube, and mechanism under the control of said exhausting means for opening said air-valve to admit air for driving a carrier along the tube when the carrier is inserted at either of said receiving stations.

20 8. In a pneumatic-despatch-tube-system, the combination of a normally closed transit-tube through which carriers are transmitted, an air-inlet valve at one end of the tube and normally closed, means for exhausting

25 air from the tube near its other end, a plurality of receiving-stations through which carriers may be inserted into the tube, and pneumatic means under the control of said exhausting means for opening said air-valve to admit air for driving a carrier along the tube when a carrier is inserted at either of said receiving-stations.

9. In a pneumatic-despatch-tube system, the combination of a pair of normally closed transit-tubes connecting two stations and having their receiving and delivery terminals at respectively opposite stations, an air-passage connecting said tubes at one of said stations, suction apparatus communicating 35 with the delivery-terminal at the other station, an air-inlet valve controlling the inflow of air to the receiving-terminal at said other station, said air-valve being normally closed, and mechanism under the control of 40 said suction apparatus and adapted to open said air-valve when a carrier is inserted into either of said transit tubes.

10. In a pneumatic-despatch-tube-system, the combination of a pair of normally closed transit-tubes connecting two stations and having their receiving and delivery terminals at respectively opposite stations, an air-passage connecting said tubes at one of said stations, suction apparatus communicating 55 with the delivery terminal at the other station, an air-inlet valve controlling the inflow of air at the receiving-terminal at said other station, said air-valve being normally closed, and mechanism under the control of said 60 suction apparatus and adapted to open said air-valve through a change of the pressure in the transit tubes.

11. The combination of a transit tube through which carriers are transmitted, a 65 gate extending across the tube and normally

closed to prevent the passage of air through the tube, means for exhausting air from the tube, pneumatic means under the control of said exhausting means for opening said gate, a trip extending into the path of the carriers in front of said gate and said trip being adapted when engaged by a carrier to cause the operation of said pneumatic means for opening the gate to permit the free passage of the carrier.

75 12. In a pneumatic-despatch-tube-system, the combination of a pair of normally closed transit-tubes connecting two stations and having their receiving and delivery terminals at respectively opposite stations, an air-passage connecting said tubes at one of said stations, suction apparatus communicating with the delivery terminal at the other station, an air-inlet valve communicating with the receiving-terminal at said other station, 80 said air-valve being normally closed, and mechanism under the control of said suction apparatus and adapted to open said air-valve when air is admitted to the transit-tubes at either of said stations.

90 13. In a pneumatic-despatch-tube-apparatus, a normally closed transit tube, an air-inlet valve extending across the said transit tube and normally closed to prevent the passage of air therethrough, means for exhausting air from said tube, mechanism for operating said air-inlet valve, an air conduit for admitting atmospheric pressure to operate said mechanism, and a valve normally closing said air conduit and provided 100 with a trip extending into the path of the carriers in front of said air-inlet valve, said trip being adapted when engaged by a carrier to cause the operation of said mechanism for opening said air-inlet valve to permit free passage of the carrier and to admit air to said transit tube for driving carriers.

105 14. In a pneumatic-despatch-tube-apparatus, a normally closed transit tube, an air-inlet valve extending across said transit tube and normally closed to prevent the passage of air therethrough, means for exhausting air from said tube, mechanism for operating said air-inlet valve, an air conduit for admitting atmospheric pressure to operate 110 said mechanism, a valve normally closing said air conduit, and means for operating said air-conduit valve to admit atmospheric pressure to said mechanism to operate the same to open said air-inlet valve to 115 permit free passage of the carrier and admit air to said transit tube for driving carriers.

120 15. In a pneumatic-despatch-tube-apparatus, a normally closed transit tube, an air-inlet valve normally closed to prevent the 125 passage of air therethrough, means for exhausting air from said transit tube, mechanism for operating said air-inlet valve, an air conduit for admitting atmospheric pressure to operate said mechanism, a valve nor- 130

mally closing said air conduit, and means for operating said air-conduit valve to admit atmospheric pressure to said mechanism to operate the same to open said air-inlet valve to admit air to said transit tube for driving carriers.

16. In a pneumatic-despatch-tube-apparatus, a normally closed transit tube, an air-inlet valve extending across the said transit tube and normally closed to prevent the passage of air therethrough, means for exhausting air from said tube, mechanism for operating said air-inlet valve, an air conduit for admitting atmospheric pressure to operate said mechanism, a valve normally closing said air conduit and provided with a trip extending into the path of the carrier in front of said air-inlet valve, said trip being adapted when engaged by a carrier to cause the operation of said mechanism for opening said air-inlet valve to permit the free passage of the carrier and to admit air to said transit tube for driving carriers, and means for timing the closing of said air-inlet valve.

17. In a pneumatic-despatch-tube-apparatus, a normally closed transit tube, an air-inlet valve extending across the said transit tube and normally closed to prevent the passage of air therethrough, means for exhausting air from said tube, mechanism for admitting atmospheric pressure to operate said mechanism, a valve normally closing said air conduit, means for operating said air-conduit valve to admit atmospheric pressure to said mechanism to operate the same to open said air-inlet valve to permit free passage of the carrier and admit air to said transit tube for driving carriers, and means for timing the closing of said air-inlet valve.

18. In a pneumatic-despatch-tube-apparatus, a normally closed transit tube, an air-inlet valve normally closed to prevent the passage of air therethrough, means for exhausting air from said transit tube, mechanism for operating said air-inlet valve, an air conduit for admitting atmospheric pressure to operate said mechanism, a valve nor-

mally closing said air conduit, means for operating said air-conduit valve to admit atmospheric pressure to said mechanism to operate the same to open said air-inlet valve to admit air to said transit tube for driving carriers, and means for timing the closing of said air-inlet valve.

19. In a pneumatic-despatch-tube-apparatus, a normally closed transit tube, an air-inlet valve normally closed to prevent the passage of air therethrough, means for exhausting air from said transit tube, a cylinder, a piston in said cylinder and connected to said air-inlet valve, an air conduit for admitting atmospheric pressure to said cylinder for operating said piston to open said valve, a valve normally closing said air conduit, and means for operating said air-conduit valve to admit atmospheric pressure to said cylinder to operate said piston to open said air-inlet valve to admit air to said transit tube for driving carriers.

20. In a pneumatic-despatch-tube-apparatus, a normally closed transit tube, an air-inlet valve normally closed to prevent the passage of air therethrough, means for exhausting air from said transit tube, a cylinder, a piston in said cylinder and connected to said air-inlet valve, an air conduit for admitting atmospheric pressure to said cylinder for operating said piston to open said valve, a valve normally closing said air conduit, means for operating said air-conduit valve to admit atmospheric pressure to said cylinder to operate said piston to open said air-inlet valve to admit air to said transit tube for driving carriers, and means for timing the closing of said air-inlet valve.

In testimony whereof, I have signed my name to this specification in the presence of two subscribing witnesses, this 10th day of February A. D. 1905.

EDMOND A. FORDYCE.
